UNITED STATES PATENT OFFICE.

ALBERT L. LAMBERT, OF PHILADELPHIA, PENNSYLVANIA, ASSIGNOR TO HEINTZ MANUFACTURING COMPANY, OF PHILADELPHIA, PENNSYLVANIA, A CORPORATION OF PENNSYLVANIA.

AUTOMOBILE DOOR.

Application filed September 16, 1925. Serial No. 56,591.

This invention relates to vehicle doors, and more particularly relates to all-metal doors for automobile bodies.

The principal object of my invention is to provide an all-metal door for vehicles which presents a window space of increased width and which at the same time is exceedingly light in weight and at the same time very sturdy and durable. Another object of my invention is to provide a door construction which is inexpensive to manufacture and is attractive in appearance. A further object of my invention is to provide improved reinforcing means for the sides of the door.

Other objects of my invention will be in part obvious and in part pointed out hereinafter.

In accordance with my invention, the door comprises frame members made up of light gauge sheet metal reenforced in a very simple manner by sheet metal reenforcing strips and by a stiffening tube running across the door at a central portion thereof.

In order that a clearer understanding of my invention may be had, attention is hereby directed to the accompanying drawings, forming a part of this application and illustrating one possible embodiment of my invention.

Referring to the drawings, Fig. 1 is a front view of a door embodying my invention, a lower corner thereof being broken away; Fig. 2 is a sectional view thereof, and is taken on the line 2—2 of Fig. 1; and Fig. 3 is a sectional view of another portion thereof, and is taken on the line 3—3 of Fig. 1. Similar reference characters refer to similar parts throughout the several views of the drawings.

Referring to the drawings, the door post at the hinge edge includes a piece of sheet metal extending the full height of the door. This piece is shaped to provide the edge wall 1 of the door, and at its outer edge is flanged outwardly, as at 2. At the inner edge of wall 1 this sheet metal piece is bent inwardly, as at 3, then forwardly, as at 4, then outwardly, as at 5, and then forwardly, as at 6. At the upper portion of the door and extending across the window opening this piece ends at flange 6. Below the window opening, flange 6 is extended and from

its end a flange 7 is broken off inwardly. A stiffening and reenforcing member 8 is disposed within this sheet metal member. 55 This member 8 is of corrugated or tortuous shape longitudinally, so that at certain portions it will abut against the wall 1, and at other portions it will abut against flange 6. Wherever this member 8 abuts either of 60 these portions 1 or 6, it is rigidly secured thereto, preferably by welding. Member 8 preferably is one piece and extends the full height of the door.

A somewhat similar construction obtains 65 along the other edge of the door. Here the post includes a single sheet of light gauge metal, shaped to present a wall 9 forming the door edge and having along its forward edge a flange 10. At the inner end of wall 70 9 the sheet metal has a portion extending inwardly, as at 11, then forwardly, as at 12, then outwardly, as at 13, and then forwardly, as at 14. At the window opening, the sheet metal ends at this flange 14, but below the window, flange 14 is extended and is broken off inwardly, as at 15. If the jamb of the door is straight, wall 9 should be straight. If the door jamb is stepped, wall 9 should also be stepped, for instance, as 80 shown. Within this sheet metal piece is placed a reenforcing and stiffening member, also of sheet metal. This reenforcing member extends the full length of the door 85 post and has a longitudinal portion 16 which is depressed or offset inwardly so as to abut flange 14. At each side of the portion 16 the reenforcing member has flanges 17 and 18, which abut against the wall 9 and follow the contour thereof, except where the tubular reenforcing member 19 extends across the door, and here the flange 18 of the re-enforcing member is straightened, so that the adjacent end of tube 19 will properly meet the same. If desired, at this point, 95 wall 18 beyond tube 19 may be flanged outwardly, as at 20, and welded, as at 21, to the wall 9. This tubular member 19 is welded at its ends to the reenforcing members on each edge of the door.

Adjacent the window opening and to each side post of the door may be secured a panel strip 22, which provides window molding and retaining means. The outer edge of

each strip 22 may be flanged over the adjacent flange of the post member, to wit, flanges 2 or 10. At its inner edge, the panel has a rabbeted window retaining portion 23, 5 one wall 24 of which rests against the adjacent post reenforcing strip and is secured thereto, preferably by welding. Below the window opening, an outer panel 25 is placed on the outer side of the door and extends 10 between the vertical door posts, the side edges of this panel being flanged about the adjacent post flanges 2 and 10. At its upper edge panel 25 is curved inwardly, as at 26, to present an attractive appearance along 15 the lower edge of the window opening. Preferably, across the top of the window a suitable panel strip 27 is extended between the tops of the vertical door post, but this panel may be omitted, if desired. Hinge 20 plates 28 are inserted between the wall 1 and the reenforcing strip 8, and are secured to this strip as by screws 29 the flange 2 and the outer door panel members 22 and 25 being cut away to allow the hinge plates 25 28 to protrude.

From the above it will be readily apparent that the door posts may be constructed exceedingly narrow in the plane of the door and in consequence, that an increased width 30 of window space is provided. It will also be apparent that the door is exceedingly light in construction, inexpensive to manufacture, and at the same time is exceedingly strong and durable. It will also be noted that the 35 vertical reenforcements are on each side of the door, one taking the hinges and by means of its irregular corrugated shape furnishes a welding surface for the bottom of the glass run and the edge of the door alternately. The other reenforcement forms a 40 continuous bridge between the edge of the door and the glass run. Strength and rigidity is enhanced by the tube which is welded between these two reenforcing members. By 45 following this construction it is possible to make a sturdy and strong door which has very narrow posts, with the result that there is a maximum expanse of window opening and a minimum of obstruction to the vision 50 of the driver and occupants of the vehicle.

As many changes could be made in the above construction and as many apparently widely different embodiments of this invention could be made without departing from 55 the scope thereof, it is intended that all matter contained in the above description or shown in the accompanying drawings shall be interpreted as illustrative and not in a limiting sense.

60 What I claim is:

1. In a door of the character described, in combination, an edge wall portion, an angular window runway portion spaced from said wall portion, and a reenforcing plate intermediate said wall portion and

runway portion, said plate being of tortuous form longitudinally and at certain portions abutting said wall and secured thereto and at intermediate portions abutting said runway member and secured thereto. 70

2. In a door of the character described, in combination, an edge wall portion, an angular window runway portion spaced from said wall portion, and a reenforcing plate intermediate said wall portion and 75 runway portion, said plate having a longitudinal portion abutting and secured to said wall and having an inwardly depressed longitudinal portion abutting and secured to said runway member. 80

3. A door of the character described, comprising, in combination, an integral piece of sheet metal formed to constitute an edge wall with a portion along one edge extending inwardly, then forwardly, then outwardly and then forwardly, to form a window runway member spaced from said wall, and a longitudinal reenforcing strip between said wall and runway member, said reenforcing strip being shaped to abut both 90 said wall and said runway member and being secured to said wall and runway member where said abutment exists. 85

4. A door of the character described, comprising, in combination, an integral piece of 95 sheet metal formed to constitute an edge wall with a portion along one edge extending inwardly, then forwardly, then outwardly, then forwardly, then inwardly, to form a window runway spaced from said wall, and a longitudinal reenforcing strip 100 between said wall and runway, said reenforcing strip being shaped to abut both said wall and said runway and being secured to said wall and runway where said abutment 105 exists.

5. In a pillar of the character described, in combination, a vertical reenforcing strip of channel shape and flanged at the mouth of the channel, and a pillar strip embracing 110 the reenforcing strip and having a portion disposed against the open face of the reenforcing strip and secured to the flanges thereof, and having a flanged portion, constituting a window runway element, positioned at the opposite face of the reenforcing strip and seating against the bottom wall of the channel, whereby said pillar strip portions are reinforced and held in position on the opposite faces of the re- 115 enforcing strip. 120

6. In a door of the character described, in combination, a pillar strip shaped to form an edge wall of the door and an angular window runway portion spaced inwardly of 125 the edge wall, and a reenforcing plate, angular in cross section, disposed between and secured to both said edge wall and said runway portion.

7. In a door of the character described, 130

- in combination, a pillar strip shaped to form an edge wall of the door and an angular window runway portion spaced inwardly of the edge wall, a reenforcing plate, angular in cross section, disposed between and secured to both said edge wall and said runway portion, and a panel strip having along one edge a complementary window runway portion secured to the reenforcing plate, said strip being secured along its other edge to the pillar strip at the edge of the door. 5
8. In a door of the character described, in combination, a sheet metal pillar strip having a door edge portion and an angular window runway portion, a panel strip flanged to form the complementary portion of the window runway, and a reenforcing member disposed between said door edge portion and both said window runway portions, and secured thereto. 15
9. In a door of the character described, in combination, a sheet metal pillar strip having a door edge portion and an angular window runway portion, a panel strip flanged to form the complementary portion of the window runway, and a reenforcing member disposed between said door edge portion and both said window runway portions, said reenforcing member having a channel formation, the base of which abuts said window runway portions and is secured thereto. 25
10. In a door of the character described, in combination, a sheet metal pillar strip having a door edge portion and an angular window runway portion, a panel strip flanged to form the complementary portion of the window runway, and a reenforcing member disposed between said door edge portion and both said window runway portions, said reenforcing member having a channel formation, the base of which abuts said window runway portions and is secured thereto, and having outwardly extending 30
- flanges at the mouth of the channel abutting and secured to said door edge portion. 45
11. In a pillar of the character described, in combination, a vertical reenforcing strip of channel shape and flanged at the mouth of the channel, a pillar strip embracing the reenforcing strip and having a portion disposed against the open face of the reenforcing strip, and having a flanged portion constituting a window runway element, a panel strip flanged to form the complementary portion of the window runway, said panel strip and the flanged portion of said pillar strip positioned at the opposite face of the reenforcing strip and seated against the bottom wall of the channel whereby said panel strip and pillar strip portions are reenforced. 50
12. In a door of the character described, in combination, a pillar strip shaped to form an edge wall of the door and having an angular window runway portion spaced inwardly of the edge wall, a panel strip flanged to form the complementary portion of the window runway and a reenforcing plate, angular in cross-section, disposed between and secured to both said edge walls, said runway portion and said panel strip. 55
13. In a door of the character described, in combination, a sheet metal pillar strip having a door edge portion and an angular window runway portion, a panel strip flanged to form the complementary portion of the window runway, and a channel reenforcing member disposed between said door edge portion and both said window runway portions, said reenforcing member having laterally extending flanges secured to said door edge portion, and the base of said channel member abutting and secured to said window runway portions. 65

This specification signed this 11th day of September, 1925.

ALBERT L. LAMBERT.
